UNITED STATES PATENT OFFICE.

TOLBERT LANSTON, OF WASHINGTON, DISTRICT OF COLUMBIA, ASSIGNOR,
BY DIRECT AND MESNE ASSIGNMENTS, TO THE LANSTON TYPE MACHINE
COMPANY, OF SAME PLACE.

PRODUCING JUSTIFIED LINES OF TYPE.

SPECIFICATION forming part of Letters Patent No. 364,522, dated June 7, 1887.

Original application filed September 30, 1885. Serial No. 178,671. Divided and this application filed July 3, 1886. Serial No. 207,157.
(No model.)

To all whom it may concern:

Be it known that I, TOLBERT LANSTON, of Washington, in the District of Columbia, have invented certain new and useful Improvements 5 in the Art of Forming Justified Lines of Types; and I do hereby declare the following to be a full, clear, and exact description of the same, reference being had to the accompanying drawings, forming a part of this specification, and 10 to the figures and letters of reference marked thereon.

This case is a division of an application filed by me September 30, 1885, and numbered 178,671. In another division of said application—*i. e.*, No. 207,156—filed contemporaneously herewith, I have shown and described certain improvements in the art of producing justified lines and forms of type, and in illustration thereof have described several modes of 20 carrying my said invention into practice. One of said modes forms the subject of the present application, and comprises that improvement in the art which consists in forming the types for each line of composition of a width varying 25 from the width of normal or standard type a percentage equal to the percentage of variation required in an unjustified line of normal or standard characters to just fill out the line.

Referring to the accompanying drawings, 30 Figure 1 is a diagrammatic view representing an unjustified line of type of normal or standard dimensions upon an enlarged scale, the outlines only of the types being shown. Fig. 2 is a similar view representing a justified line 35 of characters made in accordance with my invention. Fig. 3 is a view of a portion of a form of type composed of a series of lines constructed according to my invention.

Similar letters and numbers in the several 40 figures indicate corresponding parts.

Referring particularly to Fig. 1, let the interval between the points lettered *a* and *c* represent the length of the proposed line of composition assumed to be the width of the column, the interval between *a* and *b* the space 45 which would be occupied by the unjustified line of types of normal or standard size, and the interval between *b* and *c* the space to be filled by justification. As the space between

b and *c* represents a certain percentage of the space between *a* and *b*, it follows that if to each division of the space *a b* there be added a corresponding percentage of its width the result will be the filling out of the line. With this as the fundamental rule of procedure for the formation of each line of matter, I proceed, first, to ascertain, by measurement or otherwise, the percentage of the unjustified line of types of normal or standard size, which, if added to said unjustified line, would cause it to fill out the standard line. Having ascertained this percentage of the unjustified line, I next proceed to form the separate type, each of a width increased or varied, as compared with the normal or standard types of the same character, an amount equal to the ascertained percentage of the type. Thus in the illustration, Figs. 1 and 2, the space *b c*, to be filled by justification, is approximately ten per cent. of the space *a b*, which represents an unjustified line of normal types; hence, if there be added to each sub-division of the line *a b*, or, in other words, to each of the twenty-three normal types which we have assumed would be contained in said space ten per cent. of its width, the line will be filled out or justified. To produce type which will when associated thus exactly fill out the line *a c*, as in Fig. 2, it is therefore only necessary that they be constructed of a width ten per cent. above the normal.

In carrying out my invention it should be understood that the types for each line of composition are formed with special reference to the needs of that line alone, and the several lines are associated together in forms, as shown in Fig. 3, so that impressions may be taken from them either for direct printing or for forming matrices for stereotype or electrotypes purposes.

The variations in the width of the type herein referred to relate solely to variations in the bodies, and not to variations in the impression-faces thereof, which remain normal; and in this connection it may be stated that in the production of lines of ordinary-sized type the variations are so slight as to be imperceptible to the eye, while uniformity of spacing is obtained in greater perfection than can be seen.

cured in ordinary hand composition, where justification is effected by the employment of spaces or quads varying in width and unequally distributed.

5 I have not thought it necessary to describe herein any special mechanism for carrying my invention into effect. A competent mechanism for the purpose is, however, described in my application before mentioned, No. 178,671.

10 Having thus described my invention, what I claim as new is—

The herein-described improvement in the

art of producing justified lines of type, consisting in forming the types for a given line of a width varying from the width of normal or 15 standard type a percentage equal to the percentage of variation required in an unjustified line of normal or standard characters to just fill out the line, substantially as described.

TOLBERT LANSTON.
